UNITED STATES PATENT OFFICE

94,554

DESIGN FOR AN APPAREL RACK

Arthur A. Miller, Selinsgrove, Pa.

Application July 3, 1934, Serial No. 52,449

Term of patent 14 years

To all whom it may concern:

Be it known that I, Arthur A. Miller, a citizen of the United States, residing at Selinsgrove, in the county of Snyder and State of Pennsylvania, have invented a new, original, and ornamental Design for an Apparel Rack, of which the following is a specification, reference being had to the accompanying drawing, forming part thereof.

The figure is a perspective view of an apparel rack, showing my new design.

I claim:—

The ornamental design for an apparel rack as shown.

ARTHUR A. MILLER.
